COLUMBIA PLANOGRAPH CO., WASHINGTON, D. C.

UNITED STATES PATENT OFFICE.

ANDREW TROVATON, OF THIEF RIVER FALLS, MINNESOTA.

COIN-BOX.

1,161,909.

Specification of Letters Patent. Patented Nov. 30, 1915.

Application filed September 12, 1914. Serial No. 861,415.

To all whom it may concern:

Be it known that I, ANDREW TROVATON, a citizen of the United States, residing at Thief River Falls, in the county of Pennington and State of Minnesota, have invented a new and useful Coin-Box, of which the following is a specification.

This invention has reference to currency or coin boxes, and its object is to provide a receptacle for coins capable of holding a definite amount, and which may be utilized for storage and will also constitute a convenient means for containing coins where it is desired to utilize the coins from time to time.

In accordance with the present invention there is provided a box or receptacle containing compartments for coins of different denominations, and so arranged that when filled with coins, those portions of the edges of the coins which are exposed, and which may be termed the top portions of the coins are all on a level, or in one plane, thus permitting a cover to be applied to the box for protection.

The invention includes means whereby a definite number of coins when placed in the proper compartments are held snugly therein against rattling, but without interference with the removal of the coins, as desired.

Provision is made by the present invention for temporarily holding the cover on the box, so that it will not be accidentally displaced in ordinary handling, and yet may be quickly removed when the operator so wills.

Furthermore, provision is made by the present invention for utilizing the cover for the storage of money in the form of bills or valuable papers, or papers containing information or any other desirable form of paper which may be used in connection with the coins.

The present invention is designed particularly for use in banks or other institutions where it is desirable to have coins of different values segregated and yet handily disposed for use, while at the same time the receptacle constitutes a convenient and clean means for the storage of the coins in the vault of the bank, being economical in the matter of space.

The coin box of the present invention also provides a convenient holder for the coins when on the teller's desk, saving handling of the coins. Furthermore, the box may be

made cheaply enough to be utilized in place of the usual cloth sacks frequently employed in banks for containing relatively large sums of coin.

The invention will be best understood from a consideration of the following detailed description taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings: Figure 1 is a plan view of the coin box with the cover applied, and a portion of the cover removed to disclose the inner portions of the box. Fig. 2 is a section on the line 2—2 of Fig. 1. Fig. 3 is a section on the line 3—3 of Fig. 2. Fig. 4 is a perspective view of a portion of an elastic or spring member for holding the coins from rattling. Fig. 5 is a plan view of a portion of a modified form of box. Fig. 6 is a section on the line 6—6 of Fig. 5. Fig. 7 is a fragmentary perspective view of the paper holding attachment arranged within the cover of the box.

Referring to the drawings, there is shown a box body 1 which may be made of heavy cardboard or some other suitable material, including metal, and this box body comprises a bottom member 2, sides 3 and ends 4. Adapted to the box body is a cover member 5 having a body portion 6, sides 7 and ends 8. The width of the cover is such as to fit the box body snugly, while the cover is long enough to permit the ends thereof to be spaced a short distance from the corresponding ends of the body portion of the box. Applied to the ends 4 of the body portion of the box are catch members 9, each of which may consist of a relatively narrow strip of metal bent into a series of teeth 10 each with abrupt shoulder portions. Applied to the inner face of each end 8 of the cover is a catch member 11 consisting of a relatively narrow strip of metal fast at one end 12 to the cover member, and at the other end bent into a nose portion 13 and a manipulating end 14 projecting therefrom. Each end member 8 of the cover is formed with a slot 15 coinciding in position with the nose portion 13 of

the catch 11 and the manipulating member 14 projects through the slot 15 so as to be accessible from the exterior of the cover member. The catch 11 is sufficiently elastic to snap over the teeth 10 as the cover is applied to the box, and to engage the shoulder of one of the teeth 10 when the cover has been applied as far as needed. This prevents the removal of the cover so long as the catch is in engagement with a tooth 10, but the cover is readily released by engaging the manipulating member 14 with a finger of the hand or even with a finger nail, and withdrawing the nose 13 from engagement with a tooth 10, this being readily accomplished because of the presence of the slot 15.

Within the body 1 of the box there is located a block 16 snugly fitting the body portion of the box and secured therein in any appropriate manner. This block is of approximately the size of the body of the box and has formed in the face remote from the bottom member 2 of the body of the box a series of laterally extended channels 17 each with a rounded bottom portion and of a diameter in the direction of the length of the box corresponding to the diameter of some coin. The groove or channel 17 at one end of the box is made of sufficient size to receive coins of dollar denomination, that at the other end of the box is of a size to receive half dollars, and other channels are designed to receive quarter dollars, ten cent silver pieces, five cent nickel pieces, and one cent pieces. At the end of each channel 17 the side 3 of the box is formed with a notch 18, so shaped as to provide a convenient finger hole, whereby a stack of coins lodged in a channel is readily grasped between the fingers of the hand of the user and removed from the box, while a similar stack may be readily inserted in an appropriate channel in the box. Various coins are indicated in dotted lines in Fig. 2 at 19 as lodged within the channels 17.

Extending longitudinally through the block 16 is a groove 20 as long as the block and rising from the bottom of the block to a point quite close to the top of the block. The channels are close enough together to leave upstanding webs 21 between them dividing one channel from the other. The groove 20 extends into these webs 21 nearly to the upper edge thereof, leaving a connecting bridge 22 over the groove 20. This bridge is shown as rather thin, but may extend for a greater distance toward the body portion of the block than indicated in the drawings, this being a feature largely of manufacture.

Lodged in the groove 20 is a channel strip 23 preferably of metal and extending from the side walls of this strip at proper intervals are pairs of spring clips 24 each having its free end convex, as shown at 25, while the

stem of the clip is of sufficient length to provide for the location of the convex portion 25 within a respective channel 17. The material of the channel entering ends of the clips 24 is sufficiently elastic to permit the approach of the clips one toward the other, which may be accomplished by pressure applied thereto, but when the pressure is released the clips will spring back to their first position, which is in contact with the side walls of the groove 20.

The parts are so proportioned that a definite number of coins of the appropriate denomination may be placed in a groove with the coins face to face, the definite sum represented by the coins demanding a row of sufficient length so that one end of the row will engage against the inner wall of the side member 3 where exposed at the channel 17, while the other end of the row of coins engages the convex portion 25 of the clip 24, slightly bending this clip toward the other clip. This means that the row or stack of coins is under such elastic pressure as can be exerted by the particular clip 24 and under ordinary conditions of use this pressure is sufficient to hold the coins against rattling. Under some circumstances the clips 24 may be supplemented by other clips 24^a at the outer ends of the coin receiving channels, as shown in Figs. 5 and 6 where the channels are indicated at 17^a as formed in a block 16^a lodged in a box body 1 as before. In Figs. 5 and 6 the channels 17^a are separated by webs 21^a while the block 16^a at the ends of the channels is in-cut for a short distance, as shown at 26, to permit the clip members to have a normal location toward the clip members 24 located as before along the middle portion of the block 16^a. In this way the stacks of coins are held at both ends by elastic pressure.

The channels 17 designed to receive coins of different denominations vary in depth in accordance with the particular denominations for which the channels are adapted, and the variation in depth is such that when the channels are filled with coins the top edges of the coins, that is, those edges remote from the bottom of the box, are all in one plane, so that when the cover 5 is applied and locked in place, all the coins are engaged by the cover and clamped in the respective channels against liability of movement in a direction away from the bottoms of the channels.

Located within the cover 5 are two holding members 27, 28, the member 27 being connected to one end member 8 of the cover by a hinge 29, and the other member 28 being connected to the other end member of the cover by a hinge 30, these hinges being conveniently made of cloth strips, while the holding members 27 and 28 may be constructed of cardboard or some sufficiently

stiff and soft material. Near the hinge end of the member 28 there is provided a fastening tongue 31, while the member 27 at the end remote from its hinge is formed with an 5 entering slot 32 through which the tongue may extend, the tongue being then bent against the member 27, thus holding it to the member 28. The two members 27 and 28, each of a length approximately that of 10 the inside of the cover of the box, fold one upon the other into the cover, but are sufficiently spaced from the inner wall of the cover to permit the lodging of various papers therein, as indicated at 33 in Figs. 2 and 3. 15 These papers may consist of money in the form of bills, or they may consist of checks or any other like pieces of paper, either of value or containing information. The two retaining members 27 and 28 together with 20 any papers 33 held thereby constitute a relatively soft pad, which when the cover is applied engages the then exposed edges of coins lodged in the channels 17 and serve to hold the coins in place in a more or less 25 cushioned member, thus preventing rattling or displacement of the coins.

The spring clips at one or both ends of the coin receiving portions of the channels 17 are advantageous since coins vary sufficiently in thickness either as newly made or when some are worn more or less thin. The channels may therefore be all of the same length for the spring clips will yield sufficiently to permit some variation in the 35 lengths of the stacks of coin. Definite amounts in coin may therefore be lodged in the coin box and there held snugly irrespective of differences in denomination and differences due to wear.

40 What is claimed is:—

1. A coin box provided with a body member and a cover, the body member having receptacles for coins disposed to hold coins of different predetermined denominations 45 edgewise with the receptacles varying in depth in accordance with the sizes of the coins adapted thereto to bring the exposed edges of all the coins when lodged in the receptacles in substantially one plane, and 50 the cover of the box having on its interior overlapping retaining members, for papers and the like, together constituting a cushion for engaging the edges of the coins lodged in the channels.

55 2. A coin box comprising a body member with interior channels each of a size to receive coins of a predetermined denomination with the ends of the channels provided with closures having finger receiving notches, 60 whereby the group of coins within a channel may be grasped at the ends by the fingers of the human hand, and each channel containing an elastic member in position to engage one end of the row or group of coins 65 lodged in the channel face to face to hold

the coins against movement, the elastic member having its coin engaging portion nearer to the bottom of the channel than to the top thereof and closer to the bottom of the channel than the finger receiving notch, whereby 70 the elastic member is out of the way of the fingers.

3. A coin box provided with interior channels adapted to receive predetermined amounts of coins in face to face relation 75 with each channel having end closures provided with finger receiving notches, and an elastic member for engaging the end of a row or stack of coins within the channel and yieldable in the direction of the length of the stack of coins to hold such stack against movement, said elastic member having the coin engaging portion stopping short of the finger receiving notch to provide grasping room for the fingers of the hand in removing the stack from or placing it in the box. 80

4. A coin box provided with a block having a series of transverse channels therein for the reception of coins and with an intermediate longitudinal groove and opposed elastic members lodged in the groove and provided with portions extending into the channels to form elastic retaining members for coins deposited in the channels. 90

5. A coin box provided with an elongated 95 block therein having a longitudinal groove midway of its width and a series of transverse channels for coins, and a channel strip in the groove having pairs of clip extensions terminating in rounded extremities 100 with said extremities located within the channels in the block and constituting retaining members for coins deposited in the channels.

6. A coin box provided with an elongated 105 block therein having a longitudinal groove midway of its width and a series of transverse channels for coins, and a channel strip in the groove having pairs of clip extensions terminating in rounded extremities 110 with said extremities located within the channels in the block and constituting retaining members for coins deposited in the channels, said coin receiving channels being of different diameters and extending correspondingly different distances into the block to bring the exposed edges of all coins lodged in the channels in substantially one plane. 115

7. A coin box provided with an elongated block therein having a longitudinal groove 120 midway of its width and a series of transverse channels for coins, and a channel strip in the groove having pairs of clip extensions terminating in rounded extremities with said extremities located within the channels 125 in the block and constituting retaining members for coins deposited in the channels, said coin receiving channels being of different diameters and extending correspondingly different distances into the block to bring 130

the exposed edges of all coins lodged in the channels in substantially one plane, the clips being of correspondingly different lengths to bring the coin engaging free ends thereof 5 all in substantially the same relation to coins lodged in the channels.

8. A coin box comprising a body member and a cover member with a multi-channeled coin-receptacle lodged in the body portion 10 of the box, the channels varying in depth in accordance with the diameters of the coins to be carried to bring the exposed edges of the coins all in one plane, and coacting latch members on the ends of the body and cover 15 members, one of the coacting latch members having a longitudinal series of engaging portions for holding the cover member to the body of the box at different distances therefrom, whereby material of different 20 thicknesses may be lodged between the cover and the coins and be held in engaging relation with the exposed edges of the coins.

9. A coin box comprising a body member and a cover member with a multi-channeled 25 coin-receptacle lodged in the body portion of the box, the channels varying in depth in accordance with the diameters of the coins to be carried to bring the exposed edges of the coins all in one plane, and coacting latch members on the ends of the body member of the box and the cover member and

provided with means for holding the cover member to the body of the box in closed relation thereto at different distances therefrom, said cover member being also provided 35 with elongated holding means for papers on the inner face of the top portion of the cover of the box to constitute a cushion-retaining means for engaging the exposed edges of coins lodged in the channel member. 40

10. A coin box provided with coin receiving channels each provided with grasping room at the ends for the application of the fingers of the human hand to a stack of coins in the channel and each channel having an 45 elastic terminal member for holding the coins snugly and yieldably to variations in the lengths of the stacks of coins representing predetermined values, the elastic terminal member engaging the stack of coins to one side of the longitudinal center line thereof and on that side of the longitudinal center line remote from the finger grasping area. 50

In testimony, that I claim the foregoing 55 as my own, I have hereto affixed my signature in the presence of two witnesses.
